UNITED STATES PATENT OFFICE.

GEORGE W. KUENNETH, OF PATERSON, NEW JERSEY.

BEAMING MECHANISM.

1,362,165.

Specification of Letters Patent. Patented Dec. 14, 1920.

Application filed August 20, 1918, Serial No. 250,678. Renewed May 7, 1920. Serial No. 379,685.

To all whom it may concern:

Be it known that I, GEORGE W. KUENNETH, a citizen of the United States, residing at Paterson, in the county of Passaic and State of New Jersey, have invented 5 certain new and useful Improvements in Beaming Mechanisms, of which the following is a specification.

My present invention consists in certain 10 improvements in the beaming mechanism set forth in my Patent No. 1,246,284, the same being directed to the mounting of the beams so that they may be shifted transversely of their axes, to the mounting of the beam- 15 carrying brackets so that they may be removed, attached or adjusted with facility and convenience, and to the manner of releasably connecting the beams with their driving face-plates or equivalent.

20 In the accompanying drawings,

Figure 1 is a front elevation, certain parts appearing in section;

Fig. 2 is a plan;

25 Figs. 3 and 4 are sectional views on lines 3—3 and 4—4, looking to the right and left, respectively, in Fig. 2;

Fig. 5 is a sectional view on said line 4—4, looking to the right;

Fig. 6 is an inside elevation of the right 30 hand stand when employed in a beaming mechanism not adapted for traverse;

Fig. 7 is a side elevation of one of the beam-carrying brackets;

Fig. 8 shows a certain coupling; and,

35 Figs. 9 and 10 are longitudinal and transverse sectional views of a beam and its driving face-plate.

40 *a* is the frame of a warping machine, *b* a pair of fixed parallel guide-rods secured therein, *c* and *d* a pair of stands connected adjustably by the reach-rod *e* and slideable on the guide-rods, and *f* a screw, journaled in the frame and a bridge piece *g* fixed to the guide-rods and having its threading engaged 45 with the stand *c* and adapted to be rotated in any well known way from the shaft of the reel *h* of the machine. In the frame *a* is journaled the gear wheel *i*, suitably driven, and in the bore of said gear wheel is 50 splined the shaft *j*. The parts so far described are substantially the same as in the patent to Keyworth, No. 753,079; rotation of the gear-wheel and screw cause, respectively, rotation of the beams for winding 55 (through means to be explained) and lateral

traverse as the winding, *i. e.*, beaming, proceeds.

As the invention is herein illustrated the mechanism is adapted for ribbon beaming, including a plurality of beams; it is not essential, however, that the beaming unit include more than one beam.

k is a stand secured by clamps *k'* and bolts *k''* on the stand *c*; *l* is a companion stand bolted on stand *d*. Stands *k* and *l* afford bearings for a shaft *m* on which is fixed a pinion *n* housed in stand *k* and meshing with a pinion *o*, also housed in stand *k* and fixed to shaft *j*. While the traverse is proceeding shaft *j* slides axially of while rotating with gear wheel *i*.

Stands *k* and *l* have cap screws *p* for securing a support, consisting of end members *q*, a tie rod or shaft *r*, square in cross-section, and clevises *s*, connected to the end members 75 by the bolts *t* and having set-screws *u* to bind against the tie-rod, at different positions to which it may be shifted around the shaft *m*, which penetrates said end members; the shifting movement is limited by 80 the slots *p'* in the end members, receiving the cap-screws *p*. The tie-rod carries the several beam-carrying brackets, and it may be stayed between its ends by one or more clevises *v* each having a set-screw *w* to bind 85 against the tie-rod and secured to a collar *x* on shaft *m*.

In ribbon beaming the beams *y* are preferably arranged on opposite sides, to wit, one set inward and the other outward, of the 90 tie-rod *r*, and they are staggered, as shown in Fig. 1. For each beam there are two brackets *z* and *2*. They are secured to the tie-rod preferably so that simple manipulation permits their attachment thereto and 95 detachment therefrom and adjustment thereon to vary the spacing of the beams. Thus, Figs. 5 and 7, each has a jaw *3* to receive and fit the tie-rod, a shackle consisting of two pivotally connected links 4—5 pivoted to 100 one side of the jaw, means to lock the shackle to the other side of the jaw and means to impose binding pressure on the tie-rod. The locking means is a cam-lever *6* pivoted in the end of the shackle and engageable 105 with the locking shoulder *3'* on the jaw *3*, and a detent lever *7* pivoted in the cam lever and also engageable with said shoulder. The means to impose the binding pressure is a set-screw *8* tapped into link 4 and adapt- 110

ed to impinge against the tie-rod. When the parts are in the position shown in Fig. 7, the set-screw binding against the tie-rod, the bracket will be held immovably to the latter. If the handle end of the detent lever is elevated so that said lever clears the locking shoulder 3' the cam lever can be sprung downward to relax the tension of the shackle and so permit the bracket to be slid along the tie-rod without its falling therefrom; to remove the bracket link 5 is swung upward, after performing the described movements of the cam and detent levers, until the locking shoulder is cleared.

15 The brackets *z* simply afford bearings for the trunnions of the beams. The brackets 2 are hollow (Fig. 9), forming casings for intermeshing pinions 9, 10 and 11. Each pinion 9 is splined on the shaft *m* and each pinion 11 journaled in a bearing 12 at the outer end of the corresponding bracket 2. Pinion 11 receives in its bore the axial part or hub 13 of the face-plate 13' to which one end of a beam *y* is attached, such part having screwed into its free end the cone spindle 14 of a hand-wheel 15. In radial bores 16 in the hub are balls or like rolling keys 17 adapted to bear outward against a hardened split band 18 and so exert binding pressure on the bore of the pinion 11 when the hand-wheel is turned so as to force the cone inwardly against the keys. It is a very simple and easily effected operation to bind the face plate firmly to the pinions 11 or release them therefrom in the use of this means. It will be understood that on rotating shaft *m* from shaft *j* through pinions *o* *n* all the beams (if their face-plates are bound to their respective pinions 11 in the way explained) will be rotated through the pinions 9, 10 and 11. Pinions 9 being splined to shaft *m* the bracket 2 may be shifted along said shaft on the tie-rod in setting the beams to the required spacing.

45 In beaming it is very desirable that it be possible to alter the plane in which the material extends from the reel of the warping machine to the beam. Thus, for instance, in ribbon beaming of the class where, as above described, the beams are arranged in two sets, staggered, so that the plane of the sheet of warps to one set of beams and that of the warps to the others are not coincident, it is of considerable advantage that the positions of these planes be changeable so that the light may be made to fall to best advantage on the several warps. This indicates one object of arranging the support *q*—*r*, on which the beam-carrying brackets are mounted, so that it may be shifted, in the present adaptation around shaft *m* as an axis and in such case actually altering the distance between the two planes. Another object in constructing the mechanism so

is to make it possible to suit the position of the warps to the stature of the attendant and thus facilitate his reaching over to get at the warps which extend to the relatively inner beams.

70 In those cases where traverse during beaming is not required, the stands *k* *l* may be mounted on bases 19 bolted to cross-beams as 20 of the machine frame *a* (see Fig. 6).

Having thus fully described my invention 75 what I claim as new and desire to secure by Letters Patent is:—

1. Means to support the sheets being operated upon in different planes including rotary means on which the sheets are wound and from which they are adapted to be unwound and a plurality of rotary beams on which the sheets are respectively adapted to be wound, one beam being adjustable toward and from the sheet extending toward 80 the other beam to alter the distance between said planes, in combination with means to rotate both beams while the first beam is in any of the positions to which it is adjusted.

2. Means to support the sheets being operated upon in different planes including rotary means on which the sheets are wound and from which they are adapted to be unwound, and a beaming unit including a plurality of beams on which the sheets are 95 respectively adapted to be wound, said unit being adjustable to different positions altering the distance between said planes, in combination with means to rotate both beams while said unit is in any position to which 100 it is adjusted.

3. Means to support the sheets being operated upon in different planes including rotary means on which the sheets are wound and from which they are adapted to be unwound, and a beaming unit including a plurality of beams on which the sheets are respectively adapted to be wound, said unit being adjustable on an axis substantially parallel with the axis of the first means, in 110 combination with means to rotate both beams while said unit is in any position to which it is adjusted.

4. Means to support the sheets being operated upon in different planes including 115 rotary means on which the sheets are wound and from which they are adapted to be unwound, and a beaming unit including a plurality of beams on which the sheets are respectively adapted to be wound, said unit being adjustable on an axis substantially parallel with the axis of the first means and between the beams, in combination with means to rotate both beams while said unit is in any position to which it is adjusted. 120

5. Means to support the sheets being operated upon in different planes including rotary means on which the sheets are wound and from which they are adapted to be unwound, and a beaming unit including a plu- 130

rality of beams on which the sheets are respectively adapted to be wound, said unit being adjustable on an axis substantially parallel with the axis of the first means, in combination with means to rotate both beams while said unit is in any position to which it is adjusted including a rotary power transmitting shaft having its axis coincident with said unit.

10 6. The combination of a shaft, a beam supporting bracket arranged thereon, and means to secure the bracket to the shaft including a shackle attached to the bracket and extending around the shaft, and means 15 to put the shackle under tension.

7. The combination of a beam, and means for supporting and effecting rotation of the beam including a bracket, a rotary part journaled in said bracket in axial alinement with the beam, another part disposed and 20 with the beam, another part disposed and

movable axially in said rotary part, and means to bind said parts together including a rolling key radially movable in the axially movable part and adapted to exert binding pressure on said rotary part.

8. The combination of a beam, and means for supporting and effecting rotation of the beam including a bracket, a rotary part journaled in said bracket in axial alinement with the beam, another part disposed and movable axially in said rotary part, and means to bind said parts together including a rolling key radially movable in the axially movable part and adapted to exert binding pressure on said rotary part, and a wear-band 30 interposed between said rotary part and the key.

In testimony whereof I affix my signature.

GEO. W. KUENNETH.
